[57] CLAIM

The ornamental design for an iron support, as shown and described.

DESCRIPTION

FIG. 1 is a front elevational view of an iron support showing my new design;

FIG. 2 is a right side elevational view thereof;

FIG. 3 is a rear elevational view thereof;

FIG. 4 is a left side elevational view thereof;

FIG. 5 is a bottom plan view thereof;

FIG. 6 is a top plan view thereof;

FIG. 7 is a rear elevational view of the iron support shown ready for storage.

Cross-reference is made to a co-pending utility application filed on even date herewith.

FIG. 6
